UNITED STATES PATENT OFFICE

LADISLAS TURCHANYI, OF SASHALOM, NEAR BUDAPEST, HUNGARY, ASSIGNOR TO MAGYAR RUGGYANTAARUGYAR RESZVENYTARSASAG, OF BUDAPEST, HUNGARY, A CORPORATION OF HUNGARY

DESIGN FOR A TOY

Application filed February 13, 1933, Serial No. 47,196, and in Great Britain and Austria October 17, 1932.
Term of patent 7 years.

To all whom it may concern:

Be it known that I, LADISLAS TURCHANYI, a citizen of Hungary, residing in the village of Sashalom, near the city of Budapest, Hungary, have invented a new, original, and ornamental Design for Toy, of which the following is a specification, reference being had to the accompanying drawing forming a part thereof,

In the drawing Fig. 1 shows a perspective view of a toy embodying my new design, Fig. 2 shows an end view thereof.

I claim:

The ornamental design for a toy substantially as shown.

LADISLAS TURCHANYI.
